UNITED STATES PATENT OFFICE.

PETER D. FISCHER AND CHARLES NONNENMACHER, OF NEW YORK, N. Y.

FOLDING LOUNGE.

SPECIFICATION forming part of Letters Patent No. 240,114, dated April 12, 1881.

Application filed March 3, 1881. (No model.)

To all whom it may concern:

Be it known that we, PETER D. FISCHER and CHARLES NONNENMACHER, of the city, county, and State of New York, have invented 5 a new Improvement in Folding Lounges, of which the following is a full, clear, and exact description.

This invention relates to extension folding lounges; and it consists in so constructing 10 the same that the links which connect the two parts shall be inclosed with the frame out of sight when the lounge is closed; and it further consists in contracting the shell so that it shall be supported independently of the body 15 when opened or extended.

Figure 1 is a front elevation of the improved folding lounge closed, with parts broken away to exhibit other parts. Fig. 2 is a sectional end elevation of the same. Fig. 3 is an end 20 elevation of the same. Fig. 4 is an end elevation of the same open or extended.

Similar letters of reference indicate corresponding parts.

In the drawings, A represents the main body 25 of the folding lounge, and B the top or shell covering the main body A when closed, on the top, front, head, and foot, without showing any joints or dividing-lines on the said front or head or foot ends. Said top or shell

30 B is secured to the main body A by means of curved rotating links C, that are rigidly secured on the outside of the body A on the ends of a rod, D, that extends the whole length of the body A inside of and parallel with its front.

35 The opposite ends of said links C are secured by being pivoted with screws or pins a to lugs E, that are fastened on the inner faces of the ends of the top or shell B, so that by removing said screws or pins a the top or shell B

40 can be detached from the body A. These lugs E are so shaped as to permit the ends of the links C to be held between them and the ends of the top or shell B. The links C are secured in such a position that their convex sides, when

45 the top or shell B is closed upon the body A, are above a straight line drawn between the ends of said links C, and when the top or shell

B is opened or extended the links C are reversed in position, so that their convex sides are below such straight line, so that said links 50 C in no way interfere with the frame or wood-work of the lounge, nor do they require recesses or pockets to be formed therein for their reception, as is ordinarily the case in the construction of other folding lounges.

F F' are the folding-lounge legs, the front legs, F, projecting for about half their thickness in front of the body A, as shown at b, and the hind legs, F', projecting at the ends, as shown at c, so as to give firm support to the 60 top or shell B when the latter is closed. The shell or top B is longer than the body A by the thickness of the ends of the former and the thickness of the links C, and the ends or head and foot of said top or shell B are of sufficient length to extend flush with the rear face of the back of the body A, as shown at d, when the lounge is closed, so that no indication of the double use of the lounge can be observed at either end thereof, and the front of said top 70 or shell B also presents an unbroken line. The legs F F' raise said lounge from the floor, so that good ventilation is afforded, and are of such height that the lounge is no higher above the floor when closed than an ordinary lounge. 75

Having thus described our invention, what we claim as new, and desire to secure by Letters Patent, is—

1. In the construction of a folding lounge, the body A, provided with projecting legs F F', 80 substantially as herein shown and described, said legs serving to support the lounge top or shell when the lounge is closed, as set forth.

2. In a folding lounge, the combination, with the body A, provided with rod D, of the top 85 or shell B, lugs E, rotating curved links C, and screws a, constructed and arranged substantially as herein shown and described.

PETER D. FISCHER.
CHARLES NONNENMACHER.
